LE ROI E. HUTCHINGS, OF BUFFALO, NEW YORK, ASSIGNOR TO REMINGTON RAND INC.,
OF BUFFALO, NEW YORK

CARD HOLDER

Application filed November 9, 1928. Serial No. 313,220.

My invention relates to filing devices, and it has particular reference to a detachable filing section for a file suitable for holding theater and railway tickets or similar articles having printed matter thereon.

It is universally recognized that such articles as theater or railway tickets should be accessible to the ticket seller in order to expedite the business of selling tickets and to satisfy purchasers thereof.

The present invention contemplates the provision of a device which will retain, in a small space, a large number of such tickets in such a way that they are readily accessible and partially visible to the ticket seller so that he may complete any orders or requests for tickets with a minimum expenditure of time. Generally, the filing device forming the subject matter of this invention consists of a number of folded sheets of paper secured together at their top portions by means which serve to define pockets holding the tickets. These folded sheets are also provided with means enabling them to be secured on a filing board or in a suitable cabinet.

An illustrative embodiment of the invention is shown in the accompanying drawing, wherein:

Fig. 1 is a perspective view of a filing cabinet including a number of assembled files containing tickets.

Fig. 2 is a transverse cross sectional view of a file section.

Fig. 3 is a transverse cross sectional view of a file section with a pair of tickets disposed therein, and

Fig. 4 is a front elevational view of a file section, drawn to a reduced scale.

The file section shown in Figs. 2, 3 and 4 consists of a sheet of flexible material folded to form two overlapping portions 10 and 11. To properly define the fold the sheet is suitably perforated to provide a flexible hinge between the sections 10 and 11, as indicated by the reference numeral 12 in Fig. 4. The front section 10 is of slightly less height than the back section 11, the difference in height being sufficient to permit of the display of identifying marks on tickets placed in an upright manner between the sections

10 and 11 as indicated in Fig. 1. The sections 10 and 11 are mutually secured adjacent their top portions by means of hollow rivets 13, which pass through washers 14 placed between the sheets to serve as spacing means. 55 The washers 14, are preferably of approximately the thickness of two or three tickets.

The upper edge of each sheet 10 and 11 is covered with a folded reinforcing strip or sheath 15 of smooth flexible material such as celluloid. These strips are respectively secured to the sections by means of staples 16, a sufficient number being employed to prevent the strip from warping from the sheet. Only one edge of the sheath 15 is so secured, 60 the inner edge 17 being bent over the margin of the section. The sheath edge 17 of the outer section 10 is preferably slightly sprung in angular relation to the attached portion as shown at 18 in Fig. 2. As indicated in Fig. 3, when a pair of tickets 19 are placed in the file, the edges 17 contact with the tickets and serve to hold them in place. Upon such insertion the sheath edge 17 of the section 10 is thrust back to its normal position abutting 65 the margin of the section. This portion, being of resilient material, will thus resiliently engage and hold the ticket from accidental removal from the file section. Because of the nature of the material constituting the 70 strip 15, however, the tickets may be quickly removed from the file.

The front section 10 is recessed along its lower edge as indicated by the reference numeral 21 and staples 22 are then pressed 75 through the exposed back section 11 into a guiding and supporting strip 23 of flexible material such as heavy paper. The strip 23 is provided with laterally extending tongues 24 by means of which the file section may 80 be inserted in a suitable frame, such as that shown in Fig. 1, in a manner well understood in the art.

In practice, it will be found advantageous to dimension the sections 10 and 11 so that 85 they are about the same general height as the ticket, the section 10 being of slightly less, and the section 11 of slightly greater height. The rivets 13 may be spaced slightly 90 more than the width of a ticket so that each 95 100

pair of adjacent rivets define a pocket which will receive in an upright position as many tickets as may be placed in the pocket. The number of tickets for each pocket will, of course, depend upon the thickness of the washer 14. The binding strips 15 on the respective sections 10 and 11 should be so disposed as to be slightly in overlapping relation. With this condition, a desirable degree of flexure at two points is imposed on the tickets, retaining them in desired position.

A number of sections may be mounted in a file case, and so constitute a file for receiving all of the tickets of a given theater for a certain production, or all of the tickets for a local railroad line, or for similar classified devices, and a number of file holders may then be disposed on a rack and so constitute a complete file for the stock of the particular ticket seller.

It will be understood, of course, that these proposals are suggestive in nature, as is also the description of the preferred embodiment of the invention, and that various modifications may be made within the principles of the invention as set forth in the following claims.

What is claimed is:

1. A card holder for card index systems, comprising a sheet of flexible material formed to provide a front portion and a back portion joined together at one marginal edge, a supporting strip secured to said sheet adjacent said marginal edge, and means spaced from said marginal edge for retaining said front and back portions in spaced relation to provide pockets opening between the free marginal edges of said front and rear portions.
2. A card holder for card index systems, comprising a supporting means, front and back rectangular portions secured together at one edge and said back portion being attached to said supporting means, and means connecting said sections intermediate the supporting means thereon and the free ends thereof to form a card receiving pocket between said portions, said supporting means adapted to retain said holder in a suitable support in overlapping offset relation to an adjacent similar holder.
3. A card holder for card index systems, comprising a sheet having a central folded

portion to provide front and back portions cooperating to form a pocket therebetween, resilient sheaths connected to and extending along the free margins thereof, said sheaths defining the entry portion of said pocket, and a supporting strip secured to said sheet along the fold portion.

4. A card holder for card index systems, comprising a supporting strip, front and back portions secured together at one edge and to said supporting strip, sheaths formed of folded strips enclosing the free margins of said front and back portions, said sheaths having the fold portions on the outer faces of said front and back portions secured thereto and the fold portions at the inner faces of said front and back portions free and adapted to cooperate for frictionally retaining cards in position between said front and back portions, and means connecting said front and back portions at spaced intervals.

5. A card holder for index systems comprising a sheet folded on itself to form a front portion and a back portion, spacing members spaced from said fold, connecting and spacing said portions and dividing said connected sections into a series of spaced pockets, and a resilient sheath on the free margin of each section, said sheaths defining the entry portion of all of said pockets, and adapted to resiliently engage cards inserted in said pockets.

6. A card holder for index systems comprising a sheet folded on itself to form a front portion and a back portion, means spaced from said fold connecting said sections, and a resilient sheath on the free margin of each section and a card inserted between said sections and resiliently engaged against accidental removal by said sheaths.

7. A holder, comprising a sheet of flexible material folded to provide a front portion and a back portion, said front portion having a plurality of apertures therein adjacent to the fold portion, a second flexible member superposed on the back portion adjacent the fold portion thereof and overlying the parts of the back portion exposed through said apertures, and fasteners entered through the apertures for securing said second flexible member to the back portion adjacent said fold portion.

LE ROI E. HUTCHINGS.
